United States Patent Office.

ANN K. BENSON, OF ALLEGHENY CITY, PENNSYLVANIA.

Letters Patent No. 98,142, dated December 21, 1869.

IMPROVED HAIR-RESTORATIVE.

The Schedule referred to in these Letters Patent and making part of the same.

To whom it may concern:

Be it known that I, ANN K. BENSON, of Allegheny City, in the county of Allegheny, and State of Pennsylvania, have invented certain new and useful Improvements in Hair-Restoratives; and I do hereby declare that the following is a full, clear, and exact description thereof.

The nature of my invention consists in the combination and preparation of certain oils and essences, forming a hair-restorative, whereby the diseases of the scalp are removed, the growth of hair invigorated, and brought back to its original color.

To prepare the hair-restorative, take petroleum oil, and reduce the same, by boiling, to one-half its bulk. To four ounces (4 oz.) of the same, mix one drachm, (1 drachm,) or thereabout, of oil of citronella; and to the said mixture, add one drachm, (1 drachm,) or thereabout, of oil of bergamot, or any such like oil or essence imparting a perfume.

The said oils intermingling with the petroleum, remove its noxious smell, and also impart healing qualities.

The mixture is intended to be rubbed upon the scalp, in any ordinary manner.

Having thus described my invention,

What I claim as new, and desire to secure by Letters Patent, is—

The manufacture or preparation of a compound, which I term Benson's hair-restorative, of the oil and essences herein described, mixed, in and about the proportions set forth.

In testimony that I claim the foregoing as my own, I affix my signature, in presence of two witnesses.

ANN K. BENSON.

Witnesses:

THOMAS MALLEY,
PERCEVAL BECKETT.
